UNITED STATES PATENT OFFICE

158,637

ELECTRIC MOMENTARY CONTACT SWITCH

Arthur N. BecVar, Bridgeport, and Robert Earl Munz, Fairfield, Conn., assignors to General Electric Company, a corporation of New York

Application June 15, 1948, Serial No. 146,991

Term of patent 14 years

(Cl. D26—13)

To all whom it may concern:

Be it known that we, Arthur N. BecVar and Robert Earl Munz, citizens of the United States, residing, respectively, at Bridgeport, in the county of Fairfield, State of Connecticut, and Fairfield, in the county of Fairfield, State of Connecticut, have invented a new, original, and ornamental Design for an Electric Momentary Contact Switch, of which the following is a specification, reference being had to the accompanying drawing, forming a part thereof.

The figure is a perspective view of an electric momentary contact switch showing our new design.

We claim:

The ornamental design for an electric momentary contact switch, as shown.

ARTHUR N. BEC VAR.
ROBERT EARL MUNZ.
